(57) **CLAIM**

The ornamental design for a mobile device vehicle dashboard shelf, as shown and described.

DESCRIPTION

FIG. 1 is a perspective view of the mobile device vehicle dashboard shelf;

FIG. 2 is a front view thereof;

FIG. 3 is a rear view thereof;

FIG. 4 is a left side elevational view thereof;

FIG. 5 is a right side elevational view thereof;

FIG. 6 is a top view thereof;

FIG. 7 is a bottom view thereof; and,

FIG. 8 is a reference perspective view of the mobile device vehicle dashboard shelf installed on a vehicle dashboard and shown holding a smartphone.

The broken line showing the inside of a vehicle dashboard and smartphone is for illustrative purposes only and forms no part of the claimed design.

1 Claim, 8 Drawing Sheets
